BRASSIÈRE

George L. Diebold, Chicago, Ill., assignor to Venus Foundation Garments, Inc., Chicago, Ill., a corporation of Delaware

Application December 1, 1950, Serial No. 198,647

3 Claims. (Cl. 2—42)

1

This invention relates generally to articles of feminine apparel and more particularly to a novel type of breast support or brassière.

Brassière constructions as heretofore known have been characterized for the most part by the provision of a pair of breast pockets of fabric or the like adapted to receive and cover the breasts and to support the same. In general, such prior art constructions have been based on the principle of causing the breasts to fit into and conform to the predetermined shape of the breast pockets in order to obtain either the desired breast contour or the necessary support or both. However, due to variations in breast size, shape and contour from one woman to another and even as between the breasts of one woman, such constructions have been incapable of uniformly satisfactory support and proper fit. Brassières have been provided in different sizes and shapes as an attempted solution but such fixed graduation of size and shape was still no answer to the problem because of the virtual impossibility of accommodating all sizes and shapes within and between the fixed range. Moreover, in the previously known brassières the lifting forces of the shoulder straps have not been utilized to best advantage, such forces being distributed generally throughout the brassière body so that in many instances excessive and uncomfortable tightening of the straps has been necessary in order to obtain the desired support.

I have found that more satisfactory results can be realized by means of a brassière construction operating on an entirely different principle which permits the breast-supporting portions thereof to conform automatically to the size and shape of the breasts while at the same time providing the desired degree of support. A brassière construction based on this latter concept has the advantages of greater comfort for the wearer and more natural support of the breasts without excessive binding or restriction and hence has a wider range of application and use. Such construction, which comprises the essential feature of my invention, takes into consideration and provides for the variation in size and shape which is known to exist between the breasts of a single individual. In addition, by means of the present invention the forces exerted by the shoulder straps are transmitted directly to and are concentrated directly on the breast-supporting elements whereby to permit more effective and more comfortable adjustment of the straps.

Accordingly, a primary object of the present invention is to provide a novel and improved

5 brassière construction based on the principle of permitting the brassière to conform automatically to a substantial extent to the size and shape of the wearer's breasts, whereby to support and cover the same properly and comfortably.

10 Another object of the invention is to provide a novel type of brassière having means for individually supporting the breasts which at the same time automatically conforms to a substantial extent to the size and shape of the wearer's breasts.

15 A further object of the invention is to provide a novel brassière construction in which the breast-supporting portion can assume independently different sizes and shapes whereby to accommodate variations in size and shape between the breasts of an individual wearer.

20 An additional object of the invention is to provide a novel brassière construction in which the forces of the shoulder straps are transmitted directly and effectively to the breast-engaging portions of the brassière.

25 Other objects and advantages of the invention will become apparent from the subsequent detailed description taken in connection with the accompanying drawing wherein:

Fig. 1 is a perspective view of a brassière embodying the principles of my invention;

30 Fig. 2 is a fragmentary elevational view of the inside of a portion of the brassière on an enlarged scale;

Fig. 3 is a sectional view taken along the line 3—3 of Fig. 2; and

35 Fig. 4 is a plan view of one element of the brassière showing the shape thereof prior to assembly in the complete brassière construction.

40 Referring now to the drawing, the brassière shown therein as one specific embodiment of my invention comprises a pair of breast-receiving cups or pockets, indicated generally at 11, which may be of fabric or like material. The pockets 11 may be constructed in any suitable manner, and in the present instance each pocket is shown, by way of example, as being formed from upper and lower fabric pieces or sections 12 and 13, respectively, which are stitched together, as at 14, along a generally horizontal center line in order to provide the desired curved contour. Each of the pockets 11 is also provided at the inside thereof with an internal breast-engaging sling, indicated generally at 16, which constitutes the principle feature of my invention as hereinafter described in detail. The breast pockets 11 are connected together in spaced relation by means 45 of a triangular insert 17 which may also be of

fabric and which is attached by suitable stitching along its side edges to the inner edge portions of the pockets 11.

A pair of elongated fabric body portions or sides 18 are stitched to the outer edges of the breast pockets 11 for encircling the body of the wearer and are adapted to be detachably connected at the rear of the article by conventional means not shown. A pair of shoulder straps 19 are secured to the body portions 18 at the rear of the brassière and are adjustably connected to the tops of the breast pockets 11 at the front of the article by means of a pair of friction clips or retainers 21 of the usual type. For retaining the breast pockets 11 firmly against the wearer's body and for facilitating the supporting effect of the pockets, a band 22 of elastic material is provided below each of the pockets 11 and is stitched at its opposite ends to the center insert 17 and to the adjacent end of the corresponding body portion 18. The bands 22 may be loosely connected along their upper longitudinal edges to the adjacent lower edges of the pockets 11 by suitable means such as the loose mesh stitching indicated at 23.

As pointed out above, the prior art brassières have for the most part been constructed with breast pockets of predetermined size and shape into which the breasts of the wearer must fit without any provision for accommodating the breast-supporting portions of the brassière to the size and shape of the breasts of the particular wearer. However, by means of the breast-engaging elements or slings 16 of my device, I am able to overcome the disadvantages of the prior art constructions by providing for automatic conformity or self-adjustment of the breast-engaging portions of the brassière whereby to permit such portions to conform to a substantial degree to the size and shape of the individual's breasts.

Broadly speaking, the slings 16 comprise generally cup-like or annular members disposed at the inside of the breast pockets 11 and adapted to encircle the breasts in supporting relation whereby to provide the necessary breast support substantially independently of the outermost breast pockets. An important feature of the sling construction is that the bottom portion thereof which engages the underside of the breast is substantially non-stretchable and is secured at its ends to the body of the brassière whereby to insure firm support and uplift below the breast. An equally important feature of the sling construction is that each sling is attached to its corresponding breast pocket only at spaced peripheral points so that the major portions of the sling are absolutely free and unattached whereby to permit automatic adjustment thereof to conform to the size and shape of the breast. Although the entire sling may be formed from a substantially non-stretchable fabric, in the preferred embodiment of the invention, as described below, the side and top portions of the sling are made of elastic material to provide a yielding or self-expanding effect thereby further facilitating the automatic conformation of the sling to the breast contour.

It will be apparent that each sling 16 can be formed as a one-piece unit or, if desired, may be constructed from a plurality of pieces of different or like material. However, I have found that a particularly convenient and economical construction is obtained by means of a one-piece construction utilizing elastic material. Consequent-

ly, I have selected this latter form of my invention for purposes of illustration in the drawing, but it will be understood that the broad principles of the invention may be embodied in different constructions as suggested above.

As shown in the drawing, each of the breast-engaging elements or slings 16 is formed from a single piece of elastic material which, prior to assembly in the completed brassière, has the configuration indicated generally in Fig. 4 wherein one of the slings 16 is illustrated in flattened-out and unattached condition. The elastic material from which the slings 16 are formed is preferably of the type having stretchability in substantially only one direction. Thus, it will be seen from Fig. 4 by the direction of the elastic threads that the section of elastic as viewed therein is stretchable only in a generally vertical direction and not in a horizontal direction. It is also possible to utilize a two-way stretch elastic material for the slings 16, but it will be seen hereinafter that certain important advantages may be realized by the use of the one-way stretch material. Moreover, as hereinbefore pointed out, it is also within the scope of my invention to make the entire sling out of non-elastic material so that the sling is substantially non-stretchable throughout.

As seen in Fig. 4, the section of elastic material constituting one of the slings 16 has a generally U-shaped configuration wherein the base or bottom portion is designated by the reference numeral 24 and the legs or side portions of the section are indicated at 26 and 27. The outer ends of the side portions 26 and 27 are provided with straight end edges, as at 28, which are adapted to abut when the sling is secured within a breast pocket. The ends of the side portions 26 and 27 may also be formed with a pair of slanting end edges, as at 29, in order to facilitate the attachment of the sling to the breast pocket. The lower corners of each of the elastic sections comprising the slings 16 are preferably cut at an angle or truncated, as at 31, for a similar purpose.

Referring particularly to Figs. 2 and 3, it will be seen that each section of elastic material is assembled by pulling together the sides or legs 26 and 27 until the end edges 28 are in abutment and then stitching the ends together, as at 32, to define a cup-like or annular member having a substantially circular central opening 33. Each of the slings 16 is then secured at the inside of one of the breast pockets 11 by stitching the end edges 29 to the upper edge of the pocket 11 and by stitching the truncated corner edges 31 to the brassière along the junctures of the breast pocket 11 with the adjacent body portion 18 and the center insert 17. The manner of this attachment will be quite clear from Fig. 2 of the drawing.

With the slings secured in this manner at the inside of the breast pockets, it will be seen from Fig. 3 that each sling 16 is disposed in breast-engaging and supporting position within its pocket 11 with the central opening 33 of the sling being spaced rearwardly from the front of the breast pocket 11. Thus, the sling 16 is adapted to engage and encircle the breast with the forward portion of the breast extending through the opening 33 into the space defined between the opening 33 and the front of the breast pocket 11.

As hereinbefore pointed out, a very important feature of my construction resides in the fact

that each sling 16 is secured to the brassière by attachment at only three spaced points, namely, at the top and at the opposite sides. Thus, the bottom portion 24 and the side portions 26 and 27 of the sling are absolutely free and unattached between the aforementioned three spaced points of attachment. This will be apparent from Fig. 3 wherein an intermediate point of the bottom portion 24 is shown to be free and slightly spaced from the outermost fabric section 13 of the breast pocket 11. The side portions 26 and 27 are similarly disposed in free and unattached condition intermediate the attached ends thereof.

As a result of the three-point attachment of the sling 16 in the manner just described and as a result also of the stretchability of the elastic material comprising the slings 16, it will be readily seen that when the device is in use the slings 16 will snugly engage and encircle the wearer's breasts while at the same time expanding or stretching slightly in one direction or another in order to accommodate themselves to the size and shape of the breasts. With a one-way stretch elastic material as illustrated in the drawing, it will be understood that the side portions 26 and 27 of the sling 16 are stretchable longitudinally thereof to provide substantial conformation of the slings to the breast at the top and sides thereof, while the bottom portion 24 is substantially non-stretchable longitudinally thereof. As a result of this lack of expansion or stretchability at the bottom of the slings 16, very effective support is given to the under sides of the breasts where such support is most vital and the expandable or self-conforming characteristics of the slings is confined for the most part to the portions 26 and 27 which extend around the sides and over the tops of the breasts. Consequently, by the use of a one-way stretch elastic material in the manner shown, I am able to realize all the benefits and advantages of permitting the breast-engaging elements to accommodate themselves to the size and shape of the breasts while at the same time obtaining completely effective breast support. Moreover, it will be apparent that the use of unitary sections of elastic for forming the slings results in a very simple and highly economical construction.

The three-point attachment of the slings 16 at the top and sides thereof serves to hold the slings in open breast-supporting position and also to prevent collapse or sagging thereof. Thus, the bottom portions 24 being substantially non-stretchable longitudinally thereof and being firmly attached at their ends to the body of the brassière, there is no tendency toward undesirable sagging of the slings 16 and consequent elongation of the breasts. In addition to the importance of the spaced point attachment of the slings 16, it will also be understood that the free and unattached condition of the portions 24, 26, and 27 of the slings between their points of attachment to the brassière body is also very important in order to permit the unattached portions of the slings to stretch automatically and conform readily without restriction to the size and shape of the wearer's breast.

In order to supplement the effect of the bottom portions 24 of the slings in preventing sagging or elongation of the breasts, I prefer to secure the front ends of the shoulder straps 19 directly to the top portions of the slings 16 as well as to the top of the breast pockets 11. To this end I secure a pair of small loop portions 34 (Fig. 75

3) to the upper portions of the breast pockets by means of suitable stitching extending through the overlying top edges of the slings 16 and the breast pockets 11. The retaining elements 21 are thereby permanently attached to the brassière by means of the loops 34, and the shoulder straps 19 are detachably and adjustably affixed to the retainers 21. In this manner, the upward pull of the shoulder straps 19 is exerted directly on the slings 16 and the slings are thus supported directly by the shoulder straps. It will be seen that when the straps 19 are tightened the slings 16 connected directly thereto will be pulled into snug supporting engagement with the wearer's breasts. Moreover, when the shoulder straps are adjusted by the wearer, the adjusting forces are applied primarily to the slings 16 rather than being distributed throughout the brassière so that the wearer may more readily achieve the position thereof giving most support and comfort without excessive tightening of the straps.

It will be understood that with my brassière construction, the major breast-supporting effect is contributed by the slings 16 which are in direct engagement with the breasts. The breast pockets 11 serve as an outermost covering for the breasts but at the same time the pockets 11 will also contribute a reinforcing and supporting effect on the breasts inasmuch as in actual use the slings 16 will expand slightly and engage the inner surfaces of the fabric sections 12 and 13 comprising the breast pockets 11.

Although the invention has been described in connection with a specific structural embodiment thereof, it will be understood that various modifications and equivalents may be resorted to without departing from the scope of the invention as described by appended claims.

I claim:

1. In a brassière having a pair of breast pockets, means for independently supporting the breasts and conforming to a substantial extent to the size and shape thereof, said means comprising a pair of self-adjusting annular breast-engaging members disposed at the inside of the breast pockets and adapted to extend circumferentially completely around the breasts of the wearer in breast-conforming relation, said members each being securely fastened to its corresponding breast pocket at three spaced points adjacent the top and opposite side edges thereof whereby the remaining unattached portions of said members are free to move and conform to the size and shape of the wearer's breasts and whereby said members are retained in open breast-supporting position during use without collapse and sagging thereof and said members having substantial resistance to stretching in a generally horizontal direction at the bottom portions thereof whereby to provide a firm support below the breasts and being readily stretchable in a generally vertical direction at the side portions thereof to conform to a substantial extent to the size and shape of the breasts.

2. In a brassière having a pair of breast pockets, means for independently supporting the breasts and conforming to a substantial extent to the size and shape thereof, said means comprising a pair of breast-engaging slings secured to the inside of the breast pockets, said slings being adapted to encircle completely the wearer's breasts in uninterrupted supporting relation therewith and being fastened to the breast pockets at a plurality of spaced points adjacent the top and opposite side edges of the slings where-

by to provide unattached portions in said slings intermediate said spaced points of attachment for free yielding expansion and self-conformity, and each of said slings being substantially non-stretchable in a generally horizontal direction at the bottom portion thereof and being stretchable in a generally vertical direction at the side portions thereof whereby to conform to a substantial extent to the size and shape of the wearer's breasts while at the same time providing effective support below the breasts.

3. In a brassière having a pair of breast pockets, means for independently supporting the breasts and conforming to a substantial extent to the size and shape thereof, said means comprising a pair of elastic breast-engaging members secured to the inside of the breast pockets, said members each being formed from a generally U-shaped section of one-way stretch elastic material having an elongated bottom portion and elongated outwardly extending side portions, said side portions being secured together at the top of the member to define a cup-like sling having a central opening and said sling being fastened at spaced points adjacent its top and side edges at the inside of the corresponding breast pocket, said

10

5 sling being adapted to encircle the wearer's breast with the unattached portions of said sling intermediate the points of attachment being free for yielding expansion and self-conformity, and the one-way stretch elastic material of which the sling is formed being so arranged that the bottom portion of the sling is substantially non-stretchable longitudinally thereof whereby to provide firm support below the breast and the side portions of the sling are stretchable longitudinally thereof whereby to conform to a substantial extent to the size and shape of the wearer's breasts.

8 GEORGE L. DIEBOLD.
